CLAIM

I claim the ornamental design for a dehydrator, as shown and described.

DESCRIPTION

FIG. 1 is a front view of a dehydrator in an assembled disposition according to the present invention.

FIG. 2 is a front view of the dehydrator depicted in FIG. 1 in a storage disposition.

FIG. 3 is a left side view of the dehydrator depicted in FIG. 1 in the storage disposition, the right side view being a mirror image thereof.

FIG. 4 is a left side view of the dehydrator depicted in FIG. 1 in the assembled disposition, the right side view being a mirror image thereof.

FIG. 5 is a rear view of the dehydrator depicted in FIG. 1 in the assembled disposition.

FIG. 6 is a top view of the dehydrator depicted in FIG. 1.

FIG. 7 is a bottom view of the dehydrator depicted in FIG. 1; and,

FIG. 8 is a perspective, left side view of the dehydrator depicted in FIG. 1 in the assembled disposition.

The broken lines shown in the drawings are for illustrative purposes only and form no part of the claimed design.
